(57) CLAIM

The ornamental design for a tabletop game, as shown and described.

DESCRIPTION

FIG. 1 is a top perspective view of a tabletop game according to my design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The broken lines shown in the drawings depict portions of the tabletop game that form no part of the claimed design.

1 Claim, 4 Drawing Sheets
